[57] ABSTRACT

Incoming binary code words of $n+m+1$ bits, the highest-ranking of them being a polarity indicator, are fed to a first decoding stage which converts the lower-ranking n -bit group into a corresponding analog voltage of up to 2^n incremental steps and, in the presence of at least one bit of logical value "1" in the higher-ranking m -bit group, superimposes upon this analog voltage a fixed voltage of 2^m incremental steps. A second decoding stage simultaneously receives the m -bit group and derives from it a stepdown factor, ranging from 0 to 2^m , by which a switching circuit controlled by that stage divides the output of the first stage.

PCM DECODER WITH EXPANSION CHARACTERISTIC

My present invention relates to a demodulator for binary code words, e.g., as arriving at a receiving station in a telecommunication system of the pulse-code-modulation, time-division-multiplex type.

In digitizing an analog signal, such as the instantaneous amplitude of an audio-frequency wave, it is possible to improve the signal-to-noise ratio by magnifying the lower signal voltages with reference to the higher amplitudes in accordance with a predetermined compression characteristic and restoring the original relationship upon subsequent digital/analog analog reconversion by operating along a complementary expansion characteristic, as is well known per se. In such a compander system, the characteristics are generally knee-type curves each consisting of 2^{m+1} linear segments dividing a range of signal amplitudes, between limits of $\pm U_{max}$, into as many bands (half of them positive, half of them negative) whose width increases from the origin outward by a factor of 2, except for the two innermost bands on either side of the abscissa which are of the same width. Each amplitude band, in turn, is subdivided into 2^n incremental steps represented by the n lowest-ranking bits of a code word of $n+m+1$ bits, the highest-ranking bit being a sign indicator which, of course, is needed only if the signal to be digitized can be of either polarity.

In the specific PCM system discussed hereinafter by way of example, each code word consists of eight bits with $n=4$ and $m=3$. Thus, the characteristic is divided into 16 segments, eight on each side of the origin; if the four innermost segments of identical slope are considered a single segment, the number of segments reduces to thirteen. Reference may be made in this connection to a CCITT report entitled COM XV, question No. 33, Temp. Doc. No. 34 of 25 September to 6 October 1967.

The general object of my present invention is to provide an improved pulse-code demodulator for re-expanding the analog equivalents of binary code words generated in the aforescribed manner according to a compression characteristic divided into 2^{m+1} (or possibly 2^m) linear segments.

A more specific object is to provide means in such a demodulator for reversing the polarity of the reconstituted analog voltage under the control of the sign bit, if necessary, at a stage preceding the restoration of the original amplitude relationship in order that possible minor switching dissymmetries may be stepped down in the same proportion as the corresponding signal amplitudes to minimize their effect upon low-amplitude signals.

A further object is to obviate the need in such a demodulator for so-called floating analog switches (which do not respond to a fixed reference potential) as well as constant-current generators, both of which require complex circuitry in order to be realized with the necessary degree of precision.

Still another object is to provide a demodulator which, while satisfying the aforesaid desiderata, operates at a decoding speed compatible with the reception of 3-bit code words in a PCM system of the 30/32-channel type in which signal amplitudes are sampled during intervals on the order of 1 μ sec.

In accordance with this invention, the demodulator includes a first decoding stage connected to receive both the lower-ranking n -bit group and the higher-ranking m -bit group from a storage circuit in which the incoming code words are temporarily registered, this first stage including an impedance network with individually switchable branches which are controlled by the n -bit group to generate a corresponding analog voltage composed of up to 2^n incremental steps: a further switchable branch in this network, controlled by the m -bit group, superimposes upon this analog voltage a first voltage of 2^m incremental steps in the output of the first stage if this latter group includes at least one finite bit, i.e., if one or more m -bits thereof have the logical value "1." This m -bit group is also fed to a second decoding stage to control the operation of a weighting circuit for multiplying the output of the first stage by a factor proportional to the analog equivalent of the m -bit group. In practice, this proportional factor is usually of fractional value so that the multiplication becomes a division performed in an impedance network of the step-down type.

The network of the first stage, as more fully described hereinafter, may comprise $n+2$ parallel resistances joined to an inverting input of an operational amplifier, these resistances having staggered magnitudes $2^i R$ wherein i is an integer ranging from 0 through $n+1$, the smallest resistances thus having the value R while the largest one has the value $32R$ in the specific example ($n=4$) here considered. The smallest resistance R , which in view of the parallel connection is the electrically most significant one, is switchable into circuit in response to a finite m -bit, the register stage carrying the several (here three) m -bits working advantageously into a common OR gate to generate a control signal for the switching of this particular resistance. The largest and therefore electrically least significant resistance is connected to a source of fixed reference potential whose polarity may be reversed in response to the sign bit; it is also possible for this purpose to insert an inverter ahead of the operational amplifier delivering the output of that decoder stage, this inverter being selectively short-circuited according to the logical value of the sign bit.

Instead of staggered resistances connected in parallel branches of the impedance network, the latter may be a resistive ladder circuit of the $R/2R$ type as described, for example, by David F. Hoeschele in *Analog-to-Digital/Digital-to-Analog Conversion Techniques*, published 1968 by John Wiley & Sons, Inc., New York, pages 108 ff. This latter network comprises $n+2$ arms of magnitude $2R$ (interconnected by sections of magnitude R) of which one is connected to a source of fixed reference potential whereas the others are selectively connectable to the same source in response to respective n -bits and, in the case of the arm farthest from the source, to a finite m -bit as transmitted through the aforementioned OR gate. Again, the reversal of polarity under the control of the sign bit may be carried out at the source or by an inverter cascaded with the output amplifier.

The weighting circuit controlled by the second decoder stage may comprise a potentiometer composed of 2^{m-1} series resistors connected between a zero-voltage terminal (ground) and a high-voltage ter-

5 minal energized by the first decoder stage, these resistors having progressively decreasing magnitudes ranging from a value $2^{(2m-3)}R$ for the resistor nearest the high-voltage terminal to a value R between the two taps farthest from that terminal, the adjoining resistor at the grounded end having the same magnitude R . The high-voltage terminal and the 2^m-2 taps between the several weighting resistors are selectively connectable, under the control of the m -bit group, to an impedance transformer such as an operational amplifier whose high input resistance minimizes the shunting effect of the output circuit upon the potentiometer.

10 The duplication of the lowest resistance value at the grounded potentiometer end is designed to preserve the correct binary relationship of the several potentiometer output, at the expense of introducing an ambiguity with regard to the first two segments (of identical slope) of the characteristic curve.

15 This ambiguity, however, is resolved by the aforescribed superposition of a fixed voltage upon the analog equivalent of the n -bit group in response to the presence of at least one true m -bit; thus the switch connecting the lowest tap of the potentiometer to the output amplifier is closed regardless of the logical value of the least-significant m -bit if all the other m -bits have the logical value "0," i.e., if (for $m = 3$) this group is of either the form 000 or the form 001.

20 The operation of my improved decoder is independent of the mechanism by which the binary code words were derived from the original analog signal, provided the compression and expansion characteristics are mutually complementary. Reference may be made, however, to commonly owned application Ser. No. 120,171 filed Mar. 2, 1972 by Waldemar Fruhauf which discloses and claims a corresponding modulator operating on a somewhat analogous two-stage coding principle.

25 The above and other features of my invention will be described in detail hereinafter with reference to the accompanying drawing in which:

30 FIG. 1 is a graph of an expansion characteristic of the type used in a pulse-code demodulator embodying my invention;

35 FIG. 1a is a similar graph showing a complementary compression characteristic;

40 FIG. 1b is a graph showing part of the characteristic of FIG. 1a on a larger scale;

45 FIG. 2 is a diagram of an eight-bit code word to be demodulated;

50 FIG. 3 is an overall circuit diagram of a demodulator according to the invention;

55 FIG. 4a is a more detailed diagram of a first decoder stage forming part of the demodulator of FIG. 3;

60 FIGS. 4b and 4c show respective modifications of the decoder stage of FIG. 4a;

65 FIG. 5 shows one branch of the expansion curve of FIG. 1 on an enlarged scale, together with the output of the first decoder stage drawn to the same scale;

70 FIGS. 5a and 5b are graphs illustrating the relationship between analog voltage and code combinations in coding and decoding, respectively;

75 FIG. 6 is a table relating to the operation of a weighting circuit included in the system of FIG. 3; and

80 FIG. 7 is a circuit diagram of a second decoder stage forming part of the demodulator of FIG. 3.

Reference will first be made to FIGS. 1a and 1b which show a compression characteristic (similar to that illustrated in correspondingly numbered Figures of the above-identified Fruhauf application) as used in an encoder at a transmitting station of a PCM/TDM telecommunication system. The demodulator according to my invention, described in detail hereinafter, forms part of a receiving station linked with that transmission station in any conventional manner.

The compression characteristic shown in FIG. 1a represents the variation of the output voltage U_{out} of an amplitude converter in response to different input voltages U_{in} ranging between a negative limit $-U_{max}$ and a positive limit $+U_{max}$ of the same absolute magnitude. The positive branch of the curve, lying in the first quadrant, and its negative branch, lying in the third quadrant, are mutually symmetrical about the origin 0 and are each subdivided at points $+Q_1$ to $+Q_8$ and $-Q_1$ to $-Q_8$ into 2^m linear segments, there being eight such segments per branch ($m = 3$) in the example given. The first six segments of the positive branch have been shown more clearly in FIG. 1b; because of the symmetry, the subsequent discussion will be limited to this positive branch.

The seven knee points Q_1 to Q_7 of the curve are progressively spaced along the abscissa according to a binary law, with the exception of the first two points Q_1 , Q_2 defining bands of like width (equal to $U_{max}/128$) for the amplitude of input voltage U_{in} . Thus, the width of the third band (between points Q_2 and Q_3) is $U_{max}/64$, that of the fourth band is $U_{max}/32$, and so forth to a maximum value of $U_{max}/2$ for the eighth band. The slopes of the several linear segments defined by these knee points decrease in the same binary ratio (being identical for the first two segments) so that the output voltage U_{out} rises from one point to the next by a constant differential ΔU . With the spread ΔU quantized in 2^n steps, as indicated along the ordinate in FIG. 1b for $n = 4$, the magnitude of $+U_{in}$ may be coded in $m+n = 7$ bits. An additional bit, ranking above the others, may be used to discriminate between positive and negative polarity so that the entire range between $-U_{max}$ and $+U_{max}$ can be covered by $m+n+1 = 8$ bits.

The expansion characteristic shown in FIG. 1 is subdivided, like the aforescribed compression characteristic, into 16 segments defined by points $+P_1$ to $+P_8$ and $-P_1$ to $-P_8$ on opposite sides of the origin 0. The slopes of these segments progressively increase in a binary ratio, again with the exception of the four innermost segments (between $-P_2$ and $+P_2$) which are of the same slope; the relative length of the several segments is so chosen that their projections upon the abscissa are of uniform length, defining sixteen (2^{m+1}) sets of eight-bit code words which have been designated I - VIII for the positive half of the curve. Each set I - VIII encompasses 16 (2^n) different code words headed by a single combination of m -bits (000 through 111). Thus, the corresponding analog voltage $\pm U_A$ is divided into 16 bands whose relative width is the same as that of the corresponding bands of the original analog voltage U_{in} shown in FIGS. 1a and 1b.

FIG. 2 shows the structure of an eight-bit code word together with the digital weight of its constituent bits. The highest-ranking (sign) bit of the weight 2^7 , indicates the polarity of the transmitted signal. The next

three bits, of weights 2^6 , 2^5 and 2^4 , represent the m-bit group which defines one of the sets I – VIII in FIG. 1 and thus identifies one of the segments of the expansion characteristics whose slope determines the relative magnification or reduction to which the analog equivalent of the code word must be subjected. The four lowest-ranking bits, of weights 2^3 , 2^2 , 2^1 and 2^0 , represent the n-bit group which selects one of the sixteen subdivisions forming part of the designated amplitude band.

The incoming bits of any code word are temporarily stored in respective bistable units of a register 100 which, at a predetermined point in a cycle and under the control of a timer not shown, discharges them in parallel to two decoding stages D_1 and D_2 . Stage D_1 receives the four n-bits, the 3 m-bits, and the sign bit; only the m-bits are fed to stage D_2 which has seven outputs 101 – 107 for the control of respective switches S_1 – S_7 in a weighting circuit also including a potentiometer RD. An operational amplifier IW with a short-circuit feedback connection from its output to its inverting or subtractive input (–), having a high input resistance and an amplification factor of substantially unity, receives on its noninverting or additive input (+) the output of the weighting circuit whose switches are connected in parallel to that input. Potentiometer RD consists of seven serially interconnected resistors RD_1 – RD_7 connected between ground and an output lead 109 of decoder stage D_1 carrying an analog voltage U_A' ; switch S_7 is inserted between this lead 109 and the input of amplifier IW beyond the junction of that lead with potentiometer RD, whereas switches S_1 – S_6 are connected to respective taps of the potentiometer formed by successive junctions of resistors RD_1 – RD_7 . The relative magnitudes of these resistors are as follows:

$$RD_1 = r$$

$$RD_2 = r$$

$$RD_3 = 2r$$

$$RD_4 = 4r$$

$$RD_5 = 8r$$

$$RD_6 = 16r$$

$$RD_7 = 32r$$

From the foregoing values it will be noted that selective operation of switches S_1 – S_7 (only one of which can be closed at a time), in response to respective combinations of m-bits, applies the following potentials to the additive input of amplifier IW:

S_1	$U_A'/64$	(001)
S_2	$U_A'/32$	(010)
S_3	$U_A'/16$	(011)
S_4	$U_A'/8$	(100)
S_5	$U_A'/4$	(101)
S_6	$U_A'/2$	(110)
S_7	U_A'	(111)

Thus, the output voltage of the first decoder stage D_1 is multiplied, under the control of the second decoder stage D_2 , by a factor which ranges from 1/64 to 1 and is proportional to the analog equivalent of the m-bit code

group operating the associated switch. These switches, though shown diagrammatically as pairs of contacts, are in practice designed as solid-state electronic devices such as field-effect transistors.

- 5 The input resistance of the operational amplifier IW may be on the order of $1 \text{ G}\Omega$ so that this amplifier should have no significant influence upon the potentiometer RD.
- 10 One form of decoder D_1 has been illustrated in FIG. 4a which shows the register 100 working into a resistance network RB comprising six resistors RB_1 – RB_6 , the first five resistors being in series with respective switches BS_1 – BS_5 terminating at a bus bar 110 which is directly connected to resistor RB_6 . A further switch BS_6 is reversible under the control of the sign bit in register 100 to apply either a positive reference voltage $+U_{ref}$ or a negative reference voltage $-U_{ref}$ to the bus bar 110 and through it to the inverting input (–) of an operational amplifier V to which all the other resistors are also connected in parallel. Amplifier V has a feedback resistor R_F connected between its output, delivering the intermediate analog voltage U_A' , and its inverting input; the non-inverting input of this differential amplifier is grounded.
- 15

20 An OR gate 111 receives the 3 m-bits 2^4 , 2^5 , 2^6 from register 100 to close the switch BS_5 whenever at least one of these bits has the logical value "1," thereby connecting the resistor RB_5 to bus bar 110. Resistors RB_1 – RB_4 are similarly connected in circuit by switches BS_1 – BS_4 responding to respective n-bits 2^0 , 2^1 , 2^2 and 2^3 .

25 The relative magnitudes of resistors RB_0 , RB_1 – RB_6 , based upon the resistance R of arm RB_5 , are as follows:

$$R_F = R/2$$

$$RB_1 = 16R$$

$$RB_2 = 8R$$

$$RB_3 = 4R$$

$$RB_4 = 2R$$

$$RB_5 = R$$

$$RB_6 = 32R.$$

- If RB is the effective overall resistance of network RB in a particular switch position (regardless of the polarity of the reference voltage applied to bus bar 110), and if U_F is the input voltage at the subtractive feedback terminal of amplifier V, we can establish the relationship

$$U_F = (U_A' - U_{ref}) R_B / (R_F + R_B) + U_{ref}.$$

Since $U_A' = -\alpha U_F$ (α being the gain of amplifier V), we obtain

$$U_A' = U_{ref} \alpha (Z-1) / 1 + \alpha Z$$

where $Z = R_B / (R_F + R_B)$. With $4\alpha \gg 1$, this reduces to

$$U_A' \approx U_{ref} (1 - 1/Z) = -R_F / R_B U_{ref}.$$

It follows that the output voltage U_A' is negatively proportional to the reference voltage U_{ref} multiplied by the quotient of the resistance R_F and R_B ; the bus bar 110 may be energized with a positive or negative reference voltage U_{ref} so that U_A' may be of either sign.

The amplification factor of commonly available operational amplifiers is very large ($10^3 < \alpha < 10^6$); hence the voltage $U_F = U_A/\alpha$ is very low. Thus, the subtractive input (−) of an operational amplifier connected as an inverter is called virtual ground or summing point. It follows that, in the circuit here considered, the voltage U_{ref} is developed only across the resistor R_B which may be considered the input impedance of the inverting operational amplifier V.

It can be readily calculated that the magnitude of the network resistance R_B may assume any one of 32 different values ranging from $32R$ (with all switches $BS_1 - BS_5$ open) to $32R/63$ (with all the switches closed), corresponding to 32 discrete amplitudes for output voltage U_A' ranging from $\pm U_{ref}/64$ to $\pm 63 U_{ref}/64$. This has been illustrated in FIG. 5. Which shows that the first set I of code words, ranging from 0000000 to 0001111 (with omission of the polarity bit), gives rise to 16 discrete steps below the median line $U_A' = \frac{1}{2}U_{ref}$, the highest of these steps (simultaneous closure of switches $BS_1 - BS_4$) representing $31U_{ref}/64$. If, with switches $BS_1 - BS_4$ open, switch BS_5 closes in response to an output of OR gate 111 to connect the electrically most significant resistor RB_5 to bus bar 110, the output voltage U_A' reaches the first step $33U_{ref}/64$ in the upper half of the diagram. Thus, in the presence of one or more m-bits of logical value "1," the 16 amplitude steps represented by the various combinations of n-bits are transposed from positions below the median line (set I) to corresponding positions above that line (sets II - VIII).

The threshold $U_{ref}/64$ of the lowermost step represents a slight and practically insignificant deviation from the original analog voltage as modified by the amplitude converter at the encoder (see FIGS. 1a and 1b). This has been illustrated in FIGS. 5a and 5b, FIG. 5a showing the relationship between the voltage steps in the region of the origin and the associated code combinations at the encoder whereas FIG. 5b gives the corresponding relationship at the decoder D_1 . At the encoder, words 10000000 and 00000000 represent 0 volt, words 10000001 and 00000001 indicate a first step equal to $1/32$ of the positive or negative voltage U_1

$U_{max}/64$, words 10000010 and 00000010 relate to the next step of twice that amplitude, and so forth. At the decoder, on the other hand, words 10000000 and 00000000 respectively correspond to $+U_{ref}/64$ and $-U_{ref}/64$, words 10000001 and 00000001 denote amplitudes of $\pm 3U_{ref}/64$, words 10000010 and 00000010 designate the next unit step of $\pm 5U_{ref}/64$, and so forth.

A similar result is obtained if, as shown in FIG. 4b, the bus bar 110 is permanently connected to its source of reference voltage U_{ref} (here positive), the single operational amplifier V of FIG. 4a, being replaced by a pair of cascaded amplifiers V_1, IW_1 (the latter being of the type shown at IW in FIG. 3) between which a further inverting amplifier V_2 can be inserted with the aid of a pair of ganged switches SW_1, SW_2 under the control of the sign bit of register 100. Amplifier V_1 , generating a negative output voltage $-U_A'$, and amplifier V_2 , generating a positive voltage $+U_A'$ of the same absolute magnitude, are identical with amplifier V of FIG. 4a; in amplifier V_2 , however, the resistors R_B and R_F associated with amplifier V_1 have been replaced by a pair of identical resistors R_V' and R_V'' connected in

series between the outputs of amplifiers V_1 and V_2 with their junction tied to the subtractive input of amplifier V_2 . It can be shown that, owing to the equality of resistors R_V' and R_V'' , inverter V_2 has an amplification factor of -1 (for a gain $\alpha >> 1$) so that its insertion in or exclusion from the output circuit of the decoder does not affect the absolute magnitude of voltage U_A' delivered by impedance transformer IW_1 . In the illustrated switch position, inverter V_2 is short-circuited by switch SW_1 so that output voltage U_A' is negative; upon reversal of switches SW_1 and SW_2 in the presence of a polarity bit, this output voltage becomes positive.

FIG. 4c shows another possible configuration for the impedance network of decoder D_1 which in this case has a ladder-type structure consisting of five series resistors of magnitude R , five shunt resistors $RB_1' - RB_5'$ of magnitude $2R$ in series with respective switches $BS_1 - BS_5$, a further resistor RB_6' of the same magnitude $2R$ permanently connected to bus bar 110 at the end of the ladder remote from resistor RB_5' , and an additional resistor RB_0' connected between that end and ground. The opposite end of the ladder network RB_0' is terminated by a resistor R_L' which is virtually grounded by being joined to the subtractive input of the operational amplifier V_3 connected as an inverter. It is thus possible to consider resistor R_L' the load resistance of the ladder network across which the voltage U_A' is developed. At the output of the amplifier V_3 the voltage $-U_A'$ appears when the feedback resistors R_L'' equals the load resistors R_L' , as has already been explained for the amplifier V_2 in FIG. 4b. The voltage U_A' can be calculated in the following manner (see the above-identified publication by D.A. Hoeschele):

$$U_A' = (\frac{1}{2}D_1^* + \frac{1}{4}D_2^* + \frac{1}{8}D_3^* + \frac{1}{16}D_4^* + \frac{1}{32}D_5^* + \frac{1}{64}D_6^*) (U_{ref} \cdot R_L') / (R + R_L')$$

where $D_1^* - D_6^*$ represent the value of the respective bits controlling the switches $BS_1 - BS_6$. Again, a pair of reversing switches SV_1 and SV_2 , responsive to the polarity bit in register 100, serve to feed the output of the impedance network to an amplifier IW_2 of very high input resistance (identical with impedance transformer IW_1 of FIG. 4b) either directly or, in the illustrated switch position, by way of inverting stage V_3 .

The operation of the $R/2R$ -type ladder network RB' is well known per se. With the switches $BS_1 - BS_5$ all in their illustrated position, resistors $RB_1' - RB_5'$ are grounded and the output voltage of the network, taken off at the junctions of resistors RB_5' and R_L' , has its minimum value. In this case, and with $R_L' = 2R$, output voltage U_A' equals $U_{ref}/96$ which corresponds to the aforementioned threshold of $U_{ref}/64$ if U_{ref}' is selected to equal $3U_{ref}/2$. With this assumption the diagram of FIG. 5 applies also the circuit of FIG. 4c.

It will be understood that the various switches illustrated in FIGS. 4a - rc are also devices of the electronic type, such as bipolar transistors.

FIG. 6 is a table which summarizes the output voltages of weighting circuit RD, FIG. 3, in different positions of switches $S_1 - S_7$, together with the associated combinations of m-bits and the sets of code groups I - VIII represented thereby. A logic circuit for decoder stage D_2 , operating in accordance with that table, has been illustrated in FIG. 7 which shows seven NAND gates $N_1 - N_7$ with three inputs each except for gate N_1

having only two inputs. The outputs of gates $N_1 - N_7$ respectively control the switches $S_1 - S_7$ of FIG. 3.

Gate N_7 receives the true bits $2^4, 2^5, 2^6$, gates $N_2 - N_6$ receiving the same bits partly in negated form. Gate N_1 receives only the negated bits $\overline{2^5}$ and $\overline{2^6}$ since the logical value of the lowest-ranking m-bit (2^4) is immaterial for the operation of switch S_1 as already explained.

Thus, depending on the numerical value of the partial code combination represented by three m-bits, the weighting circuit including potentiometer RD and switches $S_1 - S_7$ attenuates the output voltage U_A' of decoding stage D_1 under the control of decoding stage D_2 to reduce the analog voltages of FIG. 5 by a corresponding step-down factor, except within the amplitude band represented by set VIII which coincides (apart from its stepped character as illustrated for sets I and II in FIG. 5) with the eighth segment of the expansion characteristic. Aside from the discontinuities inherent in digital coding and decoding, the final output voltage U_A is therefore exactly proportional to the original input voltage U_{in} (FIGS. 1a and 1b) fed into the remote encoder.

I claim:

1. A pulse-code demodulator in a receiver for binary code words of a predetermined number of bits forming a lower-ranking n-bit group and a higher-ranking m-bit group, comprising:

storage means for temporarily registering the bits of an incoming code word;

a first decoding stage connected to said stage means for receiving both said groups therefrom, said first stage including an impedance network with individually switchable branches controlled by said lower-ranking group to generate a corresponding analog voltage composed of up to 2^n incremental steps, said network being provided with a further switchable branch controlled by said higher-ranking group for superimposing upon said analog voltage of 2^n incremental steps in the output of said first stage in the presence of any finite bit in the said higher-ranking group;

a second decoding stage connected to said storage means for receiving said higher-ranking group therefrom;

and weighting means controlled by said second stage from multiplying the output of said first stage by a factor proportional to the analog equivalent of said higher-ranking group.

2. A demodulator as defined in claim 1 wherein said first stage further comprises switchover means in said network responsive to an additional bit, ranking above said m-bit group in a code work, for reversing the polarity of said output.

3. A demodulator as defined in claim 1 wherein said network includes an OR gate with input connections to respective parts of said storage means registering said

m bits, said further branch being responsive to a control signal generated by said OR gate.

4. A demodulator as defined in claim 1 wherein said first stage comprises an operational amplifier with an inverting input connected to said network.

5. A demodulator as defined in claim 4 wherein said network comprises $n+2$ parallel resistances joined to said inverting input and having staggered magnitudes 2^iR where i is an integer ranging from 0 through $n+1$, the largest resistance of magnitude $2^{n+1}R$ being connected to a source of fixed reference potential, the smallest resistance of magnitude R being switchable into circuit in response to a finite bit in said higher-ranking group, the remaining resistances being switchable into circuit in response to respective bits in said lower-ranking group.

6. A demodulator as defined in claim 5, further comprising switchover means in said network responsive to an additional bit, ranking above said m-bit group in a code work, for reversing the polarity of said source.

7. A demodulator as defined in claim 5 wherein said operational amplifier has a feedback path with a series resistance of magnitude $R/2$.

8. A demodulator as defined in claim 4 wherein said network comprises a resistive ladder circuit of $R/2R$ type with an arm of magnitude $2R$ connected to a source of fixed reference potential and with $n+1$ other arms of like magnitude $2R$ selectively connectable to said source in response to respective bits in said lower-ranking group and to a finite bit in said higher-ranking group.

9. A demodulator as defined in claim 4, further comprising an inverter ahead of said operational amplifier and switchover means in said network responsive to an additional bit, ranking above said m-bit group in a code word, for selectively short-circuiting said inverter.

10. A demodulator as defined in claim 1 wherein said weighting means comprises an impedance transformer of high input resistance and further comprises a potentiometer with 2^m-1 series resistors, a high-voltage terminal connected to said first stage for energization thereby, and an opposite grounded terminal, said resistors forming 2^m-2 taps between said terminals and having progressively decreasing magnitudes ranging from a value $2^{(2-3)}r$ for the resistor nearest said high-voltage terminal to a value r between the two taps farthest from said high-voltage terminal, the resistor lying between said grounded terminal and the tap nearest thereto having the same magnitude r , said taps and said high-voltage terminal being selectively connectable to said impedance transformer under the control of said m bits, the tap nearest said grounded terminal being so connectable regardless of the logic value of the least significant bit of said higher-ranking group upon all the other bits of the latter group having the logical value 0.
